United States Patent Office

Des. 202,285
Patented Sept. 14, 1965

202,285

RING

Louis Solomon, 3600 N. Talman Ave., Chicago, Ill.

Filed Feb. 21, 1964, Ser. No. 78,731

Term of patent 14 years

(Cl. D45—10)

Fig. 1.

Fig. 3.

Fig. 6

FIG. 1 is a top plan view of a ring embodying my new design;

FIG. 2 is a front elevational view;

FIG. 3 is a rear elevational view;

FIG. 4 is a right side view;

FIG. 5 is a left side view of the same; and

FIG. 6 is an enlarged fragmentary section taken on line 6—6 of FIG. 4.

The dominant features of the design reside in the full line portions on the drawing.

I claim:

The ornamental design for a ring, substantially as shown and described.
